UNITED STATES PATENT OFFICE.

ALBERT M. PIGEON, OF NORRISTOWN, PENNSYLVANIA.

YARN-TENSION DEVICE.

Application filed September 27, 1921. Serial No. 503,484.

To all whom it may concern:

Be it known that I, ALBERT M. PIGEON, a citizen of the United States, residing in Norristown, in the county of Montgomery and State of Pennsylvania, have invented certain new and useful Improvements in Yarn-Tension Devices, whereof the following is a specification, reference being had to the accompanying drawings.

10 My invention relates to yarn tension devices useful generally in connection with textile machinery, but more especially with knitting machines in maintaining the yarn under constant tension in the course of feed-
15 ing.

Many attempts have heretofore been made, especially in the case of knitting machines, to maintain at all times, uniform tension upon the yarn with a view toward preventing irregularities in the length of work produced. The devices employed to this end, while capable of overcoming this difficulty to a certain extent, were however not wholly efficient in attaining the real or desired objective. This inefficiency I have found to be due to their incapacity to compensate properly for variations or fluctuations in the drag or resistance of the yarn as it is drawn from supply bobbins. Such drag or resistance may vary for many reasons, amongst which the following may, by way of example, be mentioned: differences in the quality or character of the yarn; contributory effects of atmospheric conditions or changes; differences in the method or style of winding the cops or bobbins; or irregularities in the tightness of the winding.

The paramount object of my invention is to overcome the difficulty above pointed out, and this I accomplish by controlling the degree of a tension separately induced in the yarn compensatively in accordance with the magnitude of the drag or resistance offered in unwinding from the supply cop or bobbin in such a manner that a constant resultant working tension is assured.

Other objects and advantages of my invention will become apparent from the detailed description which follows:

50 In the drawings, Fig. I is a front elevation of a yarn tension device conveniently illustrating my invention; and

Fig. II is for the most part a side elevation of the same as viewed from the right of Fig. I, except for the cooperative tension disks which have been shown in axial sec-

tion so that their functioning may be more readily understood.

The several moving parts of the organization herein shown are carried or supported by an L shaped bracket 1, which may be attached, in any convenient manner, to the machine whereto yarn is to be fed. In the present instance, I have illustrated the bracket 1 as being suspended from the end 60 of a horizontal arm 2, of a yarn guide tree, (not shown), such as ordinarily employed in connection with stocking knitters, and secured by means of a screw 3 which passes through an appropriate opening in the end 65 of the arm 2, and engages with the laterally turned top portion 4 of the bracket. The vertical arm 5 of the bracket has at a point somewhat above the horizontal arm 6 an outstanding boss 7 which is axially bored for 70 anchorage of a fixed stem 8. On this stem are mounted, with capacity for free rotation, a pair of opposed tension disks 9 and 10, which as best seen in Fig. II, are dished in 75 cross section and yieldingly maintained in 80 pressure contact with each other and the end of the boss 7, by means of a helical spring 11 which encircles the stem 8. Coordinated with the tension disks 9 and 10 is a yarn guide eye 12, which is secured in the 85 horizontal arm 6 of the bracket 1 below the said disks and a spool shaped reguide element 13 located above said disks and secured to the vertical arm 5 of the bracket, preferably near the top of the latter. From 90 Fig. I, it will be observed that the tension disks, the guide eye 12 and the reguide element 13 are disposed in vertical alignment and also more especially from Fig. II that the surface of the member 13 is concaved 95 with the centre of the curvature lying in the plane of abutment of the disks 9 and 10, so that the yarn indicated at "Y" in the course of being reversed in the direction of its travel, as will be hereinafter more fully explained, is automatically maintained 100 properly centered with respect to the disks.

In order that the pressure between the disks may be compensatively varied in accordance with the drag or resistance induced in the yarn in being unwound from the supply cop or bobbin, so that a constant resultant working tension may be secured under all conditions of feeding, I have provided for cooperation with said disks, automatically operative regulating means which I will now proceed to describe. This regu-

lating means is in the form of a circular element 15, which is comparatively heavy and fulcrumed for free movement about a fixed axial pin 16 extending laterally from 5 an upstanding boss or projection 17 of the horizontal arm 6 of the supporting bracket 1. Projecting perpendicularly from one side of the element 15 is a comparatively short lug 18, which serves as a mounting for a 10 yarn eye 19. From Fig. I, it will be observed that the element 15 is offset with respect to the bracket 1 to permit registry of the movable yarn eye 19 with the stationary guide eye 12 previously referred to. The element 15 is held from displacement upon its fulcrum shaft 16, in the position shown by a collar 20 adjacent its inner side, and a cotter pin 21 which engages with the protruding end of the shaft 16. Integrally formed 15 with the collar 20 is an arm 22, whose outer end is bifurcated to afford stops 23 and 24, which are adapted, by cooperation with the lug 18, in limiting the extent of free oscillation of the element 15.

25 The movements of the regulator element 15 are communicated to the spring 11 through the instrumentality of the down turned, flattened end of a finger 25 which plays within a slot 26 at the outer extremity of the mounting stem 8, and engages with the corresponding end of said spring. Operative in opposition to the pull of the yarn as it passes through the yarn eye 19, is a counterweight in the form of an integral lug 27 of the element 15. Said lug, it will be noted, projects from the outer face of the element adjacent the periphery of the latter, and is disposed on the side of the fulcrum shaft 16 opposite to that of the yarn eye 19 30 in an angular position, and at a point above the level of the fulcrum so that its leverage, and consequently its effectiveness, increases gradually as the element is rotated clockwise and vice versa when the element is 35 moved in the counterdirection. By this construction the counterweight serves to gradually augment the action of the spring as additional tension is needed, and thus precludes the possibility at any time, of the 40 spring becoming retro-active upon the same.

45 Adjustment of the counterweight of the element 15 may be had by shifting of a collar 28 along a rod 29 extending in a direction diametrically of the element from the lug 27 clearly shown in Fig. II, as a result of which the pull on the eye 19 is counterbalanced to a greater or lesser extent. By 50 this provision, the regulating means may be set to maintain any desired resultant working tension in the yarn in satisfying demands of practice.

55 In operation, the yarn "Y" as it is drawn from the supply cop or bobbin (not shown) is guided by the stationary eye 12 to pass 60 tangentially between the tension disks 9 and 10 at one side of the mounting stem 8. After emerging from between the disks, the 65 yarn continued in its upward travel and passes about the member 13, by which it is reguided to move downwardly and reeve 70 tangentially between the tension disks 9 and 10 at the opposite side of the stem 8. Following the course of the yarn still further, it will be observed to pass again through the 75 stationary guide eye 12 and is thereafter 75 diverted from a vertical path to pass horizontally through the movable eye 19 carried by the regulator element 15, from whence it is directly led to the needles of the knitting machine. By reason of the several abrupt 80 changes in the direction of the travel of the yarn and the uniform pressure exerted by the disks by the spring 11 under the normal functioning of the regulator, the 85 yarn will be maintained at a constant even tension in the course of being fed to the consuming machine. If, for any reason, the 90 drag or resistance of the yarn in unwinding from the cop or bobbin should become heavier, the added pull will, through the 95 instrumentality of the movable eye 19, cause the regulator element 15 to be shifted counterclockwise with the result that the finger 25 will be correspondingly moved to relieve the spring 11 in accordance with the magnitude of the added pull. Such action will 100 obviously cause diminution of the pressure between the disks 9 and 10, so that the resultant or working tension of the yarn as it is fed to the knitting machine will be the 105 same as under normal operation. Again, let it be assumed that the drag of the yarn in unwinding from the supply cop or bobbin should for any reason become lighter, such relaxation in the pull will allow the 110 regulator element 15 to shift in a clockwise direction under the action of its counterweight 27, with the result that the power of the spring 11 is augmented, and the pressure between the tension disks correspondingly increased to bring about a constant resultant working tension as before. The 115 regulator element 15 is rendered proof against spasmodic impulses by virtue of the inertia due to its bulk, and undue oscillation thereof is prevented by the stops 23 and 24. The proportioning of the various constituent parts of the structure is such that all needed regulation of the tension of the 120 spring may be controlled within the limit of free oscillation of the disk 15 imposed by the stops 23 and 24. In normal operation, the lug 18 "floats" at a point approximately midway between said stops.

125 By controlling the tension of the yarn in accordance with my invention, I am enabled to produce work which is absolutely uniform as to stitch length regardless of the character of the knitting, thus not only obviating losses due to irregularities such as hereinbe-

fore pointed out, but, in addition, effecting considerable saving in the yarn.

Having thus described my invention, I claim:

5 1. A yarn tension device comprising, means for applying tension to yarn while feeding the same to textile machines, means responsive to variations in drag impressed upon the yarn controlling the tensioning 10 means to compensatively vary the tension, and means to restrain said responsive means against spasmodic actuation.

15 2. A yarn tension device comprising, means for applying tension to yarn while feeding the same to textile machines, means responsive to variations in drag impressed upon the yarn controlling the tension means to compensatively vary the tension, and a relatively heavy movable member adapted 20 by virtue of its inertia to restrain said responsive means against spasmodic actuation.

25 3. A yarn tension device comprising a pair of opposed tension discs; between which yarn is passed enroute from a supply cop or bobbin to the machine being fed; a spring for maintaining yielding pressure between said discs; in combination with regulating means adapted to respond to variations or fluctuations in the resistance or drag of the 30 yarn in unwinding from the supply cop or bobbin, including, a freely fulcrumed element sufficiently heavy to be proof against spasmodic impulses; an attached eye through which the yarn is passed; an adjustable 35 counterweight operative in opposition to the pull upon said eye; and a finger whereby movements of said element are communicated to the aforesaid spring for the purpose of compensatively increasing or decreasing the 40 pressure between the tension discs to insure a constant resultant working tension during feeding of the yarn.

45 4. A yarn tension device comprising a pair of opposed tension discs between which yarn is passed enroute from a supply cop or bobbin to the machine being fed; a spring for maintaining yielding pressure between said discs; in combination with regulating means adapted to respond to variations or fluctuations in the resistance or drag of the yarn 50 in unwinding from the supply cop or bobbin including, a circular element capable of freely oscillating about its own axis, and sufficiently heavy to be proof against spasmodic impulses; stops for limiting the extent of free oscillation of said element; a 55 guide eye for the yarn attached to the element at one side of its fulcrum; a counterweight, adapted to be operative in opposition to said guide eye, attached to the element at the opposite side of its fulcrum and disposed in an angular position above the level of the fulcrum; and a finger whereby 60 the movements of the element are communicated to the aforesaid spring for the purpose

of compensatively increasing or decreasing the pressure between the tension disc so as to insure a constant resultant working tension during the feeding of the yarn.

5. A yarn tension device comprising a pair 70 of opposed tension discs; means located beyond said discs whereby the yarn, after having passed tangentially between the discs at one side, is reversed in the direction of its travel and reguided to repass in a like manner 75 between the discs at the opposite side; in combination with resilient means for maintaining yielding pressure between said discs; and regulating means coordinated with the aforesaid resilient means for varying the pressure between said discs compensatively in accordance with variations or fluctuations in the resistance or drag offered in unwinding from the supply cop or bobbin 80 to insure a constant resultant working tension during feeding of the yarn.

6. A yarn tension device comprising a pair of opposed tension discs between which the yarn is passed, said discs being mounted for free rotation upon a fixed supporting 90 stem; a stationary guide eye located to one side of said discs in the plane of abutment of the latter; a reguide element located at a point at the opposite side of said tension discs whereby the yarn, after having been 95 guided through the aforesaid stationary guide eye and between the discs at one side is reguided to pass in a like manner between the discs at the opposite side and then again through the stationary 100 guide eye; and a spring for maintaining yielding pressure between said tension discs; in combination with regulating means coordinated with the aforesaid spring for varying pressure between said discs compensatively in accordance with the variations or fluctuations in the resistance or drag offered in unwinding from a supply 105 cop or bobbin, to insure constant resultant working tension during feeding of the yarn.

7. A yarn tension device comprising an L shaped supporting bracket; a pair of opposed discs between which yarn is passed, said discs being mounted for free rotation upon a stem projecting horizontally from the vertical arm of said bracket; a stationary guide eye secured in the horizontal arm of the bracket below said discs in the plane of abutment of the latter; a reguide element secured to the vertical arm of said bracket 110 at a point above said tension discs, whereby the yarn, after having been guided through the aforesaid stationary guide eye and between the discs at one side, is reguided to repass in a like manner between the discs at the opposite side and then again through said stationary guide eye; a spring for maintaining yielding pressure between said tension discs; in combination with a regulator element adapted to respond to variations 115 120 125 130

4

or fluctuations in the resistance or drag of the yarn in unwinding from a supply cop or bobbin including: a circular element adapted to oscillate freely about a horizontal axle shaft extending laterally from the end of the horizontal arm of the aforesaid bracket, said element being sufficiently heavy to be proof against spasmodic impulses; an auxiliary guide eye attached to the element at one side of its fulcrum, and through which the yarn is passed enroute from the stationary guide eye to the machine being fed; a counterweight adapted to be operative in opposition to the pull upon the auxiliary guide eye, said counterweight being carried by the element at the opposite side of its fulcrum and disposed in an angular position above the level of the fulcrum; and a finger whereby movements of the disc are communicated to the aforesaid spring for the purpose of compensatively

increasing or decreasing the pressure between the tension discs to insure a constant resultant working tension during the feeding of the yarn.

25

8. A yarn tension device comprising, means for applying tension to yarn while feeding the same to textile machines, means responsive to variations in drag impressed upon the yarn controlling the tensioning means to compensatively vary the tension, and means operable by inertia to restrain said responsive means against spasmodic actuation.

30

In testimony whereof, I have hereunto signed my name at Philadelphia, Pennsylvania, this 15th day of September, 1921.
